UNITED STATES PATENT OFFICE.

ALBERT GEORG KOECHLIN, OF BASEL, SWITZERLAND.

WEFT-SPPOOL CHANGER FOR WEAVING-LOOMS.

1,346,095.

Specification of Letters Patent.

Patented July 6, 1920.

Application filed May 1, 1919. Serial No. 294,030.

To all whom it may concern:

Be it known that I, ALBERT GEORG KOECHLIN, a citizen of the Swiss Republic, and resident of Basel, Switzerland, have invented new and useful Improvements in Weft-Spool Changers for Weaving-Looms, of which the following is a full, clear, and exact specification.

In known weft spool changers for weaving looms the loaded spool is generally introduced into the shuttle by means of a stationary pusher which is independent of the lay and is depressed for thrusting the spool into the shuttle ready to receive it, before the lay arrives at its forward dead-point.

The present invention relates to a changer in which the pusher is actuated to introduce the fresh spool into the shuttle not only, as hitherto, before the dead-point position of the lay, but also at any later position of the lay up to the moment when the throw of the shuttle begins. For this purpose the pusher, which in known manner shares the movement of the lay, remains during its travel in coöperative relationship with an arm adapted to depress it for introducing the spool into the shuttle; the mechanism of known kind for operating this arm, independently of the driving mechanism of the lay, when the weft fails is so arranged that the depression of the pusher may occur in the desired manner.

Advantageously the arm is operated for depressing the pusher by means of a revolving cam disk brought into coöperative relationship with the arm by an automatic coupling, the coupling movement being due to a weft stop motion.

The accompanying drawings show two constructions in accordance with the invention:

Figure 1 is a vertical section through a loom fitted with one of the constructions;

Fig. 2 is an enlarged side elevation of the weft stop motion;

Fig. 3 is a corresponding plan view;

Fig. 4 shows by vertical section the aforesaid coupling with the coöperating parts;

Fig. 5 shows in front view the weft spool pusher mounted on the lay;

Fig. 6 illustrates diagrammatically the second construction.

As is usual in weft spool changers, there is on one side of the loom a mechanism for putting the changer in action, this mechanism being dependent upon a weft stop mo-

tion comprising a fork and an oscillating lever. In the present instance (Figs. 1-5) there is a slide bed 1 on which are adapted to slide a rod 2 of rectangular section and a rack 3. The former carries a bracket 4 on which are pivoted the weft feeler fork 5 and the pawl 6 which moves the rack 3 (Figs. 2 and 3). When the weft thread fails and the fork 5 has in consequence been engaged in known manner by the oscillating lever 7 (Fig. 1), the outward swing of the latter pushes the rod 2 against the action of a spring (not shown) and through this rod a lever 8 mounted on the usual shaft 13 which extends across the loom for operating the changer. This movement of lever 8, therefore, puts in action the changer on the other side of the loom. At the same time the pawl 6 moves the rack 3 one step outward against the action of its spring 3^a.

Behind the pawl 6 a detent 9, turning on a stationary pivot 10^a, engages the rack 3, so that when the lever 7 swings inward again the pawl 6 rides over the teeth of the rack 80 while the latter remains at rest.

Both pawl 6 and detent 9 have downwardly extended tails, 6^a and 9^a respectively, with which coöperates a tappet 10 oscillating with the lever 7. In normal working of the loom this tappet each time it swings outward with the lever 7 presses on the tails 6^a and 9^a and raises both pawl and detent from engagement with the rack 3, so that rod 2 and this rack remain in or assume 90 normal position. Thus when the weft thread fails the pawl 6, as already stated, moves rack 3 outward during the outward swing of lever 7, while during the next inward swing of the latter the rack remains held by detent 9 in the new position. If the weft thread fails only at one throw the next outward movement of the lever 7 raises both pawl 6 and detent 9 in the aforesaid manner and rod 2 and rack 3 return to normal 95 position. On the other hand, if the spool changer does not operate at once and the weft thread fails at the next throw, the pawl 6 will advance the rack a second step outward, whereby the tail 6^a of the pawl is withdrawn beyond the range of movement of tappet 10, so that now a projection 3^b on the tail of rack 3 can engage the usual 105 spring lever 12 of the weft stop motion, and the loom is stopped.

According to the pitch of the teeth of the rack 3 and the position of the latter rela-

tively to that of the spring lever 12, the stopping of the loom may occur after a third or fourth failure of the weft thread. The pawl 6 and the detent 9 are so arranged that when the lever 7 swings backward, the tappet 10 allows the detent 9 to fall correctly for locking the rack. Before the loom is again started after such a stoppage, the weaver presses on the tails 6^a and 9^a in order to raise the pawl and detent and thus to allow the parts 2 and 3 to return to normal position.

The turning movement of shaft 13, caused by the thrust of rod 2, is transformed on the other side of the loom, by means of an arm 14^a on the shaft, into rectilinear movement of a sliding rod 14 carrying rack teeth which engage a pinion 15. A crank pin on the latter is connected by arm 16 with one end of a lever 17, the other end of which carries a fork engaging the sliding sleeve 18 of a clutch 19 on the pin 21. The sleeve 18 carries an arm 22 on which is adjustably mounted a roller 23 bearing against a rotating cam disk 24 but normally out of the path of the cam 31 thereof. The counterpart 20 of the clutch 19 has an arm 25 which extends over an adjustable cross head 26 (Fig. 5) on the spool-pusher 27. The latter moves to and fro in space together with the lay 28 in which it is mounted to slide up and down, being normally held in its highest position by springs 30. It can move with the lay unhindered by the arm 25. When, however, the turning of shaft 13 determines the engagement of the coupling 19, the roller 23 comes into the path of the cam 31 of the cam disk 24 and is raised so as to depress the arm 25 and therefore the pusher 27 which expels from the spool carrier a loaded spool into the shuttle, the latter having in the meantime arrived beneath the pusher. The cam disk 24 and the parts co-operating with it are so arranged that the introduction of a new spool into the shuttle occurs during a period of time within which the driving shaft of the lay (crank shaft) performs a quarter revolution, and that the depression of the pusher begins about the moment when the lay has arrived at its forward dead point and must be ended when, the dead point position having been passed, the shuttle throw begins. This condition is here quite possible since the pusher always shares the movement of the lay. The moment when the pusher acts may be adjusted within certain limits by adjusting the cam disk 24, so that the feed of a new weft spool may be made to occur before the forward dead point or after it up to the beginning of the shuttle throw. By means of this construction the shuttle may have the same speed as in the usual loose reed loom.

Whereas, therefore, in the hitherto known automatic looms, which must always be fixed

reed machines, the shuttle must be already in its place in the change shuttle box of the lay, when the driving crank of the lay is about the vertical position, in the present case the shuttle in any kind of loom can smoothly continue to run and need not be in its place in the shuttle box until the driving crank of the lay has arrived at its dead point. Thus a gentle, smooth stroke for the throw of the shuttle can be retained.

Instead of the coupling mechanism described the actuation of the spool pusher may be brought about by moving the cam disk 24 so as to bring it into operative relationship with arm 25.

Other modes of actuating the spool pusher are available; for instance a treadle mechanism may be used. A construction of this kind is shown in Fig. 6. Here the spool pusher 27 is carried by a slide rod 32 which is guided on the lay 28 and is held normally in its highest position by springs 35.

A forked treadle arm 33 engages the lower end of the rod 32 and is subject to the revolving cam disk 24 which at the required moment is moved into such relation to the treadle arm that it operates the latter to move the pusher downward.

What I claim is:

1. In an automatic weft replenishing loom, an oscillating lay, a shuttle arrangement, a pusher for introducing a full weft spool into the empty shuttle, said pusher being movably mounted on the lay so as to be capable of being lowered thereon, an actuating arm for the pusher, arranged in co-operative relationship therewith, an independent device for automatically operating the said actuating arm, weft failure detecting means to set said operating device into operation when the weft fails, said operating device having co-operating means for determining the operation for said actuating arm, substantially as and for the purpose described.

2. In an automatic weft replenishing loom, an oscillating lay, a shuttle arrangement, a pusher for introducing a full weft spool into the empty shuttle, said pusher being movably mounted on the lay and so as to be capable of being lowered thereon, an actuating arm for the pusher, arranged in permanent sliding contact therewith, an independent device for automatically operating the said actuating arm, weft failure detecting means to set said operating device into operation when the weft fails, said operating device having co-operating means for determining the operation for said actuating arm, substantially as and for the purpose described.

3. In an automatic weft replenishing loom, an oscillating lay, a shuttle arrangement, a pusher for introducing a full weft spool into the empty shuttle, said pusher being

movably mounted on the lay so as to be capable of being lowered thereon, an actuating arm for the pusher, arranged in coöperative relationship therewith, an independent rotary cam disk for operating the said actuating arm, an intermediate arm arranged for coöperating with said cam disk, a coupling between said intermediate arm and said actuating arm, and a weft stop motion connected to said coupling to close the same for a weft spool change operation when the weft fails, substantially as and for the purpose described.

4. In an automatic weft replenishing loom, an oscillating lay, a shuttle arrangement, a pusher for introducing a full weft spool into the empty shuttle, said pusher being movably mounted on the lay and so as to be capable of being lowered thereon, an actuating arm for the pusher, arranged in coöperative relationship therewith, an independent rotary cam disk for operating the said actuating arm, an intermediate arm arranged for coöperating with said cam disk, a coupling between said intermediate arm and said actuating arm, and a weft stop motion connected to said coupling to close the same for a weft spool change operation when the weft fails, substantially as and for the purpose described.

5. In an automatic weft replenishing loom, an oscillating lay, a shuttle arrangement, a pusher for introducing a full weft spool into the empty shuttle, said pusher being movably mounted on the lay and so as to be capable of being lowered thereon, an actuating arm for the pusher, arranged in coöperative relationship therewith, an independent rotary cam disk for operating the said actuating arm, an intermediate arm arranged for coöperating with said cam disk, a coupling between said intermediate arm and said actuating arm, and a weft stop motion connected to said coupling to close the same for a weft spool change operation when the weft fails, substantially as and for the purpose described.

10

erative relationship therewith, an independent rotary cam disk for operating the said actuating arm, a coupling, one member of which carries said actuating arm, an intermediate arm carried by the other coupling 25 member and arranged to be brought into coöperative relationship with said cam disk when the coupling is closed, and a weft stop motion connected to said coupling to close the same for a weft spool change operation 30 when the weft fails, substantially as and for the purpose described.

In witness whereof I have hereunto signed my name this 12th day of April, 1919, in the presence of two subscribing witnesses. 35

ALBERT GEORG KOECHLIN.
